UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

TAKE-UP MECHANISM FOR LOOMS.

Application filed March 17, 1921. Serial No. 453,030.

To all whom it may concern:

Be it known that I, JONAS NORTHRUP, a citizen of the United States, residing at Hopedale, in the county of Worcester and

5 State of Massachusetts, have invented certain new and useful Improvements in Take-up Mechanism for Looms; and I do hereby declare the following to be a full, clear, and exact description of the invention, such as 10 will enable others skilled in the art to which it appertains to make and use the same.

The present invention relates to an improvement in take-up mechanism for looms.

In the take-up mechanism illustrated in 15 the co-pending application of the present inventor, Serial No. 316,549, filed August 11, 1919, to which reference may be had, provision was made for disengaging the worm from the change gear to permit the letting 20 back of the cloth manually to any extent desired. This was done by taking hold of the handle on the take-up pawl and disengaging it from the change gear after which the operator would turn the wind-up roll by hand 25 for the purpose of letting back the cloth. While this was entirely practicable so far as the operation of the machine was concerned it has been found to be impractical from the weaver's point of view because the gear 30 which the operative took hold of soiled his hand and this is highly objectionable as it entailed the later soiling of the cloth from the hand of the operative.

The object of the present invention is to 35 produce a construction by which the wind-up roll may be turned back for letting back the cloth and forward again for taking it up to any desired extent with greater facility and without soiling the hands of the operative. To the above ends the present invention 40 consists in the take-up mechanism hereinafter described and particularly defined in the claims.

In the accompanying drawing, Fig. 1 is a 45 sectional elevation of a portion of the loom showing the improved take-up mechanism; and Fig. 2 is a front elevation of the same.

In general, the take-up mechanism comprises a wind-up mechanism, automatic let-back mechanism actuated upon the absence 50 of filling to let back the cloth, and a device for automatically limiting the amount of let-back having provision whereby different grades of cloth are let back a uniform number 55 of picks without adjustment of the de-

vice to compensate for changes in the grade of cloth. Provision is also made for operating the let-back mechanism independently of the limiting device.

The take-up mechanism illustrated in the 60 drawing is described as follows: The cloth 10 is wound upon a wind-up roll 12 yieldingly maintained against a draw roll 13, so as to be frictionally driven thereby. The draw roll 13 is positively rotated by means 65 of the gear train 14, 15, 16, 17, 18 and 19. The gear 19 is known as the change gear and is adjustably mounted in a slotted bracket 29. The change gear 19 meshes with a worm 20 on a shaft 21 driven from the cam 70 shaft 22 by bevel gears 11. The worm 20 is adapted to be moved out of engagement with the change gear 19 and subsequently moved into engagement therewith as follows: the shaft 21 carrying the worm 20 is supported 75 in a bracket 23 slidably mounted on studs 24 and 25, which in turn are extended from a second bracket 26 bolted to the loom frame. The stud 24 is provided with a cam 30 pivotally mounted thereon adapted to engage 80 cam lugs 31 and 32 extended from the surface of the bracket 23 and arranged so that the movement of the cam 30 causes movement of the bracket 23 vertically upwards and then vertically downwards as the cam is 85 oscillated back and forth. So far as the present invention is concerned the oscillations of the cam 30 are controlled and actuated by the movement of the weft hammer 33 and detector slide 34 when the filling is 90 absent. The means by which this is accomplished form no feature of the present invention, but reference may be had to said application for a fuller disclosure thereof. Suffice it to say for the present purposes that 95 the cam arm 48 formed upon the cam 30 is connected by means of a link 47 with the change lever 42 secured to the rock lever 41. The change gear 19 is engaged by a holding pawl 60 arranged so that its point engages 100 the teeth of the change gear at all times. This pawl is pivoted on the stud 63 and it is provided with a handle 68 by which it may be moved by hand to disengage it from the change gear. When it is desired to disengage the worm 20 from the change gear 19 independently of actuation of the weft hammer 33, the handle 68 is pulled upon to disengage it from the teeth of the change gear and the lug 69 secured to the lower end of 110

the pawl 60 engages the lower end of the change lever 42 and causes the same to be swung to the right, as viewed in Fig. 1, about the pivot pin 57 independently of the 5 rock lever 41 thus operating through the link 47 and cam arm 48 to turn the cam 30 so as to lower the bracket 23 to cause the disengagement of the worm 20 from the change gear 19. The cloth roll is now free to be let 10 back manually and moved forward again to any extent desired, whereupon the pawl may be dropped into engagement with the teeth of the change gear again and the parts thereby returned to their original position. The 15 disengagement of the pawl from the change gear by pulling upon the handle 68 results in the disengagement of the worm gear 20 from the change gear, and thereupon the cloth is free to be let back manually to any 20 desired extent. For this purpose a hand operated pinion 100 is provided which engages the gear 16 by the turning of which the draw roll 13 may be rotated backwardly to let back the cloth. This pinion 100 is mounted on a 25 pinion shaft 101 by a bracket 102 bolted on the frame of the loom. The shaft 101 is provided on its outer end with a hand wheel 103. It will thus be seen that by turning the hand wheel with the hand the draw roll may 30 be turned to let back the cloth, or may be

turned in the opposite direction to take-up the cloth again.

This hand operated pinion affords a highly convenient means for letting back the cloth without subjecting the operative to the inconvenience of soiling his hands necessarily required by the weaver to be kept clean and without subjecting the hands to the danger of injury from contact with the gears or by being caught in the gears.

I claim—

1. A take-up mechanism for looms having, in combination, a wind-up mechanism, driving means therefor including a worm and gear, a holding pawl, a single lever for releasing the holding pawl and disconnecting the worm and gear, and a hand wheel and pinion for actuating the wind-up mechanism in either direction when the worm and gear are disconnected.

2. A take-up mechanism for looms having, in combination, a wind-up mechanism, driving means therefor, including disconnecting means, a holding pawl, connections between the pawl and the disconnecting means arranged to operate the disconnecting means when the pawl is disengaged, and a hand wheel connected with the wind-up mechanism to turn it in either direction.

JONAS NORTHROP.
